UNITED STATES PATENT OFFICE.

HARRY T. SCOTT, OF LOS ANGELES, CALIFORNIA.

RECORD-EJECTOR FOR RECORD-CABINETS.

1,288,229.

Specification of Letters Patent. Patented Dec. 17, 1918.

Application filed April 5, 1917. Serial No. 159,867.

To all whom it may concern:

Be it known that I, HARRY T. SCOTT, a citizen of the United States, residing at Los Angeles in the county of Los Angeles, State 5 of California, have invented new and useful Improvements in Record-Ejectors for Record-Cabinets, of which the following is a specification.

This invention relates to cabinets for 10 filing phonograph records of the disk type and for filing like articles of any nature; and it is an object of this invention to provide a simple and effective means for withdrawing or ejecting records from such a cabinet wherein the records are filed or held and wherein the records are placed as closely together as possible so as to cause the economical utilization of the space.

It is an object of this invention to provide 20 record removing or ejecting means in a very simple form, capable of simple and inexpensive manufacture; and in a form capable of extension by simple duplication of parts; and in such a form that the assembly of the 25 simple parts of the device is very expeditious and inexpensive. It is further a primary object of this invention to provide such a device having a very simple form of operation. The mode of operation of the 30 ejecting device is a new and distinctive feature of my invention. I am aware that heretofore devices have been proposed and used in which a record may be pushed out by manual action—by pressure upon a lever, 35 button, or the like; but my invention involves nothing of this character. On the contrary, it involves an action in which a spring or equivalent means is released by manual action to eject the record; wherein, 40 preferably, the spring, etc. is energized by the insertion of the record; and wherein the releasing action may be by pressure upon a button or the like or upon the record itself. In the latter form, which is the preferred 45 form, a mere inward pressure upon the record itself, moving the record back slightly from its normal position, causes the release and operation of the record ejecting mechanism. If a certain record is desired, it is 50 only necessary to push slightly inwardly upon that record when the record will be immediately moved out into the hand that gave it the backward push.

All of these and other objects and features of my invention are explained in the following specification; wherein, for the

purposes of indicating and illustrating the invention, I explain in detail two specific forms of mechanism embodying the invention; reference being made for this purpose 60 to the accompanying drawings wherein Figure 1 is a vertical section of a cabinet and one form of device embodying my invention; Figs. 2, 3 and 4 are enlarged detail views showing some of the various positions which 65 may be taken by the moving parts of the device; Fig. 5 is an enlarged detail section taken as indicated by lines 5—5 on Figs. 1 and 6; Fig. 6 is an enlarged partial section taken as indicated by line 6—6 on Fig. 1; 70 Fig. 7 is a further enlargement of certain parts shown in Fig. 6; Fig. 8 is a section similar to Fig. 1, illustrating another form of device embodying the invention; Fig. 9 is an enlargement of parts shown in Fig. 8; 75 Fig. 10 is a reverse view of the parts shown in Fig. 9; Fig. 11 is an enlarged view taken substantially as indicated by line 11—11 on Fig. 8, parts being shown in section; Fig. 12 is an enlarged section taken as indicated by 80 line 12—12 on Fig. 8; and Fig. 13 is an enlargement of parts of Fig. 12.

I describe the form shown in Figs. 1 to 7 and then the form shown in the remaining figures of the drawings. After considering 85 these descriptions it will then be apparent in what features the two forms are similar and contain in common the broader features of the drawings. It will then be apparent in what features the two forms are similar and 90 contain in common the broader features of my invention, and in what features the preferred form differs from the other.

In the drawings I show a cabinet 10 which may be of any suitable size, design, or configuration, and which may form a part of any phonograph cabinet, etc. This cabinet 10 may have any kind of suitable guides for guiding the records 11 into proper place. For instance, it may have horizontal strips 12 placed upon the bottom board 13 upon which the lower edges of the records rest; the records being held in vertical position, as shown in Figs. 1 and 6. My device is made to operate upon records of 105 any size; and, as illustrating this capability of my device, I illustrate some large sized records 11 and also some small sized records 11^a. The records are put into the cabinet through suitable slot openings 14 in 110 the front wall 15 of the cabinet. I prefer to show the device acting upon records filed

in vertical positions, but this is not necessarily so. It suffices to say that the precise means of holding and guiding the records in vertical position form no part of the present invention; the present invention is not limited to any particular means for such purpose, but may be used in conjunction with any such means. In the purpose of preventing accidental removal of the records, and to prevent their rolling out of the cabinet if the cabinet should be not quite level, I provide a short incline at 13^a on the bottom board 13, which incline tends to keep the records back in the cabinet.

15 When in their proper positions, the records 11 and 11^a project slightly in front of the front wall 15 of the cabinet so as to facilitate that backward movement which is initially given them by hand before they are ejected. The position of the records is shown in Fig. 1. In this position the back edges of the records rest against ejector levers 20; or, preferably, the back edges of the records rest within the channel shaped lower end parts 20^a of these levers 20. (Although the record ejecting members may be of any form, I prefer to make them as levers). The forward open edges of these channel shaped lever parts 20^a are preferably substantially wider than the records themselves, so that as the records are moved rearwardly their rear edges will not miss the levers 20, but will enter the channel shaped parts 20^a without fail. A lever 20 is provided for each record space and for each record; and all of these levers 20 are hung upon a pivot shaft 21 which extends across the back part of the cabinet. This pivot shaft 21, in common with two other shafts or rods 22 and 23, may be supported at the ends in any desired manner, as by having the ends enter a suitable bracket 24 which may be secured to the side wall 25 of the cabinet, as shown in Fig. 6. The shaft 21 and the rods 22 and 23 may, and preferably are, supported in triangular relation to each other, when viewed as in Fig. 1; and these parts 21, 22 and 23 support a plurality of triangular plates 26. Each 50 of the parts 21, 22 and 23 may have spaced circular grooves cut or otherwise formed therein, as shown at 26^b; and the triangular plates 26 are merely slipped into place between the rods into these grooves 26^b without having to be threaded over the rods. This is shown in the various views. Each plate has notches 26^c and 26^d for engaging the rods; and, if the rods are long they may be held together by an encircling wire or wires 29, as shown in Figs. 1 and 7. There is one triangular plate 26 for each lever 20; and each lever 20 is pressed laterally against its triangular plate 26 by a spring 27, one end of this spring being 65 connected with lever 20 at the point 27^a

(see particularly Fig. 7) and being connected with the next plate 26 at the point 27^b. The arrangement is such that the spring 27 not only tends to press the lever 20 into proper position against its triangular plate 26, but also tends to rotate the lever in the direction indicated by the arrows in the various views; that is, each spring tends to move the lever in such a direction as to push the record out of the 75 cabinet.

Each lever 20 has an upwardly extending part 30, formed as an integral continuation of one side of the channel shaped part 20^a of the lever; and this upper part 30 of the lever is adapted to engage with certain stops which are of such a nature as to hold the parts in the various normal positions shown in the drawings. For instance, consider the positions shown in Figs. 1 to 5. In Figs. 1 and 5 the lever 20 is shown in full lines in normal position in coöperation with a large record 11. The upper end part 30 of the lever then bears rearwardly against the forward edge of a spring tongue 31 which stands out (is preferably punched or stamped out) from the triangular plate 26 in the manner best shown in Fig. 5, the part 30 in this position then overlying another spring tongue 32 which lies alongside and forward of the spring tongue 31. Spring tongues 31 and 32 are preferably stamped out of the metal of the triangular plate 26, and may be stamped out of the plate as a single tongue, being separated by a separating split or slit as shown. Each of the tongues 31 and 32 is turned to an angular or diagonal position, (see Fig. 5) so that the part 30 may engage the forward edge of the rear tongue 31 while overlying the forward tongue 32. The forward tongue has this function; that the part 30 must be moved forwardly a certain specified distance (the width of the tongue 32), and the lower part of the lever 20 must be moved backwardly 110 a corresponding distance, before the part 30 will not, upon subsequent backward motion, go back and engage the forward edge of tongue 31. When the lever 20 is moved sufficiently to move the part 30 ahead of the 115 forward edge of tongue 32, then the spring tongues spring outwardly to the position shown for the tongues 31^a and 32^a in Fig. 5; and, upon its backward motion, the part 30 must pass under the spring tongue 32 and under the spring tongue 31 and pass back until it engages the stop 33. The spring tongues 31 and 32 are made of springy material; or they may have their resilient quality given them in any other 125 preferred manner. The whole plate 26 may be made of suitable springy material, and the spring tongues 31 and 32 merely stamped out of the plate. The normal position of these spring tongues is the same as that 130

shown for spring tongues 31^a and 32^a in Fig. 5, in which position the part 30, which also stands in a diagonal position, will pass behind the tongues on its backward motion. 5 Spring tongues 31^a and 32^a are placed so as to be engaged by the upper end part 30 of the lever 20 when the lever is in position to coöperate with a small record 11^a. As many sets of tongues 31 and 32 may be provided as 10 there are different sizes of records desired to be filed; the positions of these tongues upon the plate 26 depending upon the general arrangement of the parts and upon the sizes of the records; but the showing of the 15 parts for handling two sizes of records is sufficient to clearly illustrate the invention. It will be understood that, in this specific form of device, there is a resilient relative movement as between the tongues 31 and 32 20 and the lever part 30. I prefer to put the resiliency in the tongues 31 and 32; although it may be readily seen that the arrangement could be otherwise. In instance, the part 30 might be resilient, or all the parts 30, 31 and 25 32 might be resilient.

In Figs. 2, 3 and 4 are shown the typical position of the lever for a small record; and the description of the operation for a small record will be sufficient to cover the operation 30 for any sized record. In Fig. 3 the rear edge of lever part 30 is shown bearing back against the forward edge of the spring tongue 31^a; and this is the position in which the part 20^a of the lever is in engagement 35 with the record 11^a. (See the dotted line showing in Fig. 1). Suppose now, that the record 11^a is pushed slightly rearwardly; then the part 30 is moved forwardly so that its rear edge is moved to a position forward 40 of the forward edge of spring tongue 32^a. The tongues 31^a and 32^a then spring outwardly to the positions shown in Fig. 5; and the part 30 may then move rearwardly, under the pressure of the spring 27, passing 45 behind the spring tongues. In so passing behind the spring tongues it may be that the part 30 must press the tongues outwardly, farther away from the plate 26 than their normal position; but this is easily done. It 50 is only necessary that, in the normal positions of the tongues, the rear edge of part 30 should be able to enter behind the forward part of tongue 32. The position of the part 30, when the record is pushed rearwardly, is shown in Fig. 4. Immediately 55 the rearward pressure on the record is released, then the spring 27 rotates the lever in the direction indicated by the arrows in the various views, and moves the part 30 rearwardly under the spring tongues 31^a and 32^a until the part 30 is brought up 60 against the stop 33. This stop 33 may be stamped out of the triangular piece 26. Such movement of the lever pushes the record 65 out beyond its normal position, and be-

yond the normal positions of all the other records lying alongside this record; so that this particular record may then be grasped and removed from the cabinet. It is not necessary that the desired record be moved 70 very far out of the cabinet; it is only necessary that it be moved out a short distance beyond the front edges of the adjacent records, so that its forward edge may be 75 grasped. The arrangement is preferably 80 made that the records in their normal positions project forwardly beyond the front wall 15 of the cabinet by just the amount necessary for rearward movement to accomplish the release of the lever and cause its immediate action to eject the record.

When a record is being put into the cabinet it is pushed in only as far as its normal position, shown in Fig. 1. When pushed to this position the part 30 moves to the position shown in Fig. 1, (or in Fig. 3) and the lever is then checked from pushing the record out, until the record is pushed farther inwardly, as hereinbefore described.

In Figs. 8 and following I illustrate a 90 structure which is, in its essentials, similar or identical in form with the structure hereinbefore described; and the description just given applies to the form of device shown in these figures as far as the same numerals are 95 applied to these figures, 8 and following. The distinctive features of construction and operation of the device of Fig. 8 will now be described. Plates 26^a, similar to plates 26, are mounted upon the same rods, 21, 22 100 and 23; and the upper end portion 30 of the lever 20 projects up alongside each plate 26^a. In this form the upper end of the lever is provided with a lip 30^b adapted to engage teeth or other serrations 50 formed upon the 105 upper laterally turned edge of a member 51 which is secured, as as 52, to the back face of each plate 26^a; the serrations 50 projecting through an opening 53 in the plate 26^a. The lip 30^b is of such formation that it may drag 110 forwardly over the serrations 50 when the lower part 20^a of lever 20 is pushed rearwardly; and the serrations will hold the lever from its record ejecting movement. When a record is put into place and the 115 lever pressed back, moving the lip 30^b forwardly over the serrations 50, then the lever is held in its ultimate position. I provide manually operable means for releasing the lever from the check formed by the teeth 120 50; and this means may preferably be in the form of a means to move the teeth 50 back beyond the surface of the plate 26^a, thus moving the teeth away from the lip 30^b. This being done, the lever actuating spring 27 will 125 then of course immediately move the lever to eject the record.

The member 51 is preferably made of spring material and is secured at its lower end, or lower ends, at 52, to the plate 26^a. 130

On the back side of the plate 26^a a pair of ears 55 is turned out to make bearings for a longitudinally slidable push rod 56. This push rod extends out to the front of the cabinet where it may be pushed inwardly by the finger or thumb; being normally held outwardly by a spring 60. Pieces 57 are also stamped out of the member 51 and have apertures which engage over cone-shaped parts 58 of the push rod; and the relation of the parts is such that when the push rod is pushed rearwardly, then the cone-shaped parts 58 act as wedges operating upon the parts 57; with the result of moving the parts 57, and the member 51, back away from the plate 26^a, so as to draw the teeth 50 back out of engagement with the lip 30^b. Thus, whenever any push rod 56 is pushed inwardly, the corresponding record ejecting lever 20 is released and its spring 27 then immediately pushes the record out a certain distance, until the lever contacts with the stop 33.

From the foregoing detailed description it will be seen that the two specific forms herein described have certain features in common. In both of these forms the insertion of the record energizes the ejecting mechanism; it energizes or tenses the ejecting spring. Of course, the spring may have a certain initial tension, but the insertion of the record has the general effect of further tensing the spring. The energy which finally ejects the record is supplied mainly to the ejecting device at the time of inserting the record rather than at the time of ejecting the record. In either case the operation of ejection involves only the operation of releasing the ejecting mechanism—allowing the ejecting spring to operate. The essential difference between the two specific forms herein explained is in the releasing mechanism or device. In the form first explained the release is accomplished by a slight rearward movement of the record itself; while in the form last explained the release is made by direct movement of the checking mechanism which normally holds the ejecting lever from operation. Thus, my general invention involves essentially a recording ejecting mechanism adapted to be released to eject a record; and preferably adapted to be energized by insertion of the record; and my preferred form of mechanism involves a releasing device for the ejecting mechanism, which releasing device is operated by a rearward movement of the record itself. I do not consider my invention as limited to the particular and specific mechanical features herein set forth; but rather do I consider it as embodying generally the combination and elements indicated and typified by the specific means herein described. While I have proceeded to

describe preferred forms of my invention in some particularity and detail, I have done so for the purpose of rendering my invention plain and intelligible, and not for the purpose of limitation; considering my invention not to be limited except as expressly set forth in the following claims. These claims are intended to cover the general invention herein described, both broadly and specifically.

Having described a preferred form of my invention, I claim:

1. A device of the character described, comprising in combination a record ejecting member, means for actuating the ejecting member to eject a record, said means being energized by the insertion of the record, check means to hold the ejecting member from ejecting the record, and means actuated by an inward movement of the record to release the checking means and allow the record to be ejected outwardly.

2. A device of the character described, comprising in combination a record ejecting member adapted to move to eject a record, means checking said movement of the record, ejecting member, and means for causing release of the record ejecting member from said checking means when the record is moved slightly in a direction opposite to that in which the record ejecting member moves it.

3. A device of the character described, comprising, in combination, a substantially vertical record ejecting lever pivoted near its upper end and adapted to engage a record with its lower part, spring means for moving said lever to eject a record, a spring tongue check normally engaging the ejecting lever, and means whereby rearward movement of the lower part of the lever causes its release from the check.

4. A device of the character described, comprising in combination a movable record ejecting member and spring means to move the member to eject a record, means checking said record ejecting movement of the member, and means for causing release of the member from the checking means by virtue of a slight initial movement of the member in the direction opposite to its record ejecting movement.

5. A device of the character described, comprising in combination, a movable record ejecting member and spring means to move the member to eject a record, means checking said record ejecting movement of the member, and means for causing release of the member from the checking means by virtue of a slight initial movement of the member in the direction opposite to its record ejecting movement, said two last mentioned means embodying a spring tongue extending diagonally across the path of movement of

said member and having a checking shoulder intermediate its ends.

6. In a device of the character described, the combination of a plurality of transversely extending plates spaced longitudinally apart, means for supporting said plates embodying a pivot rod, a record ejecting lever pivoted on the pivot rod adjacent each plate, a spring for each lever around the rod and between the lever and the next plate pressing the lever against its plate and tending to rotate it in a direction to eject a record, and manually releasable lever catch means carried by each plate.

15 7. In a device of the character described, the combination of a plurality of transversely extending plates spaced longitudinally apart, means for supporting said plates embodying a pivot rod, a record ejecting lever pivoted on the pivot rod adjacent each plate, a spring for each lever around the rod and between the lever and the next plate pressing the lever against its plate and tending to rotate it in a direction to eject a record, lever catch means carried by each plate, and means operable by a slight inward movement of the record to release the lever from the catch means and allow the lever to be moved outwardly by its spring to eject the record.

8. In a device of the character described, the combination of a plurality of supporting rods extending along the back of a cabinet, spaced plates supported transversely on and between said rods, one of said rods being a pivot rod, a record ejecting lever pivoted on said pivot rod adjacent each plate, and hanging substantially vertically, the lower part of the lever being channel-shaped to receive the edge of a record and the upper part of the lever lying close to its plate, a coiled spring around the pivot rod in each space between the spaced plates, one end of the spring being connected to and bearing against the lever and holding it against its plate and tending to rotate the lever in a direction to move its lower part forwardly to eject the record, and manually releasable catch means carried by each plate to engage

its lever to normally hold it from record ejecting movement.

9. In a device of the character described, the combination of a plurality of supporting rods extending along the back of a cabinet, spaced plates supported transversely on and between said rods, one of said rods being a pivot rod, a record ejecting lever pivoted on said pivot rod adjacent each plate and hanging substantially vertically, the lower part of the lever being channel-shaped to receive the edge of a record and the upper part of the lever lying close to its plate, a coiled spring around the pivot rod in each space between the spaced plates, one end of the spring being connected to and bearing against the lever and holding it against its plate and tending to rotate the lever in a direction to move its lower part forwardly to eject the record, catch means carried by each plate to engage its lever to normally hold it from record ejecting movement; and means, operable by a slight rearward movement of the lever caused by a corresponding movement of the record, to release the lever from the catch means.

10. In a device of the character described, the combination of a cabinet having a guide for holding a disk record standing on edge, a movable ejecting member mounted in the cabinet and against which member the record is rolled rearwardly when put into the cabinet, the guide having a rearwardly inclined surface on which the record stands to cause the record to normally press back somewhat against the ejecting member, a means tending to move the member forwardly, and releasable checking means for the member to prevent its forward movement, said checking means being releasable by a slight initial rearward movement of the record and said ejecting member.

In witness that I claim the foregoing I have hereunto subscribed my name this 30th day of March, 1917.

HARRY T. SCOTT.
